Term of patent 14 years

(Cl. D40—1)

FIG. 1.

FIG. 2.

FIG.3.

FIG. 4.

FIG.5.

FIG.6.

FIG. 1 is a front perspective view of a lawn mower for golf course greens or the like embodying my new design;

FIG. 2 is an enlarged top plan view thereof;

FIG. 3 is an enlarged elevational view taken from one side thereof;

FIG. 4 is an enlarged elevational view taken from the side opposite that shown in FIG. 3;

FIG. 5 is an enlarged front elevational view thereof;

FIG. 6 is an enlarged rear elevational view thereof.
The handle has been broken away in FIGS. 2 through 6 for convenience of illustration.

The dominant features of the design reside in the portions shown in full lines.

I claim:

The ornamental design for a lawn mower for golf course greens or the like, as shown and described.
